Patented Feb. 1, 1966

203,602

GROUP INSTRUCTION TABLE

Mary S. Dusman, 1726 Claridge Ave., Arcadia, Calif.

Filed Mar. 2, 1964, Ser. No. 78,835

Term of patent 14 years

(Cl. D33—14)

FIG. 1 is a top plan view of a group instruction table showing my new design;

FIG. 2 is a side elevation thereof;

FIG. 3 is a front elevation thereof;

FIG. 4 is a rear elevation thereof;

FIG. 5 is a perspective view thereof on a somewhat enlarged scale; and

FIG. 6 is a sectional view thereof taken on the line 6—6 of FIG. 5.

The dominant features of my design reside in the portions shown in full lines.

I claim:

The ornamental design for a group instruction table, substantially as shown and described.
